UNITED STATES PATENT OFFICE.

THOMAS H. ABERCROMBIE, OF TUMBLING SHOALS, SOUTH CAROLINA.

CHURN-DASHER.

SPECIFICATION forming part of Letters Patent No. 324,511, dated August 18, 1885.

Application filed May 14, 1885. (No model.)

To all whom it may concern:

Be it known that I, THOMAS H. ABERCROMBIE, a citizen of the United States, residing at Tumbling Shoals, in the county of Laurens 5 and State of South Carolina, have invented a new and useful Improvement in Churn-Dashers, of which the following is a specification, reference being had to the accompanying drawings.

- 10 My invention relates to an improvement in churn-dashers; and it consists in the peculiar construction and combination of devices that will be more fully set forth hereinafter, and particularly pointed out in the claim.
- 15 In the accompanying drawings, Figure 1 is a side elevation of a churn-dasher embodying my invention. Fig. 2 is a plan view of the same. Fig. 3 is a vertical central sectional view.
- 20 A represents a dasher-rod, on the lower end of which is journaled a dasher, B. The dasher B has four radial blades, C, which are inclined at an angle of about forty-five degrees. Through each of the blades C is cut an inclined slot, D, the angle of which corresponds 25 with the angle of the blades, these slots serving to increase the bearing-surfaces of the blades, and also to permit the ready passage of the cream therethrough as the dasher is worked up and down in the churn, and to 30 lighten the labor of operating the dasher. On the dasher-rod, a slight distance above the dasher B, is journaled a similar dasher, E, having blades F, that are inclined in the direction opposite to that of the blades C, and 35 slots G in the blades F, the angle of which corresponds to the inclination of said blades. The dashers B and E being loose on the dasher-rod, and their blades being inclined in opposite 40 directions, are caused to rotate in opposite directions when the dasher is operated. Centrally on the opposing faces of the dashers are secured metallic plates H, through which the dasher-rod passes. A sleeve, I, is placed 45 on the dasher-rod between the dashers, and on the dasher-rod are screwed nuts K, one of

which bears against the under side of the lower dasher, and the other of which bears against the upper side of the upper dasher, and thus keep the dashers in place upon the dasher-rod.

A churn-dasher thus constructed is cheap and simple, is very durable, can be readily taken apart when necessary in order to clean it, and is thoroughly efficient, producing butter from cream in a very short time and without laborious exertion.

I am aware that it has been heretofore proposed to construct churn-dashers with radial inclined blades provided with correspondingly-inclined open slots to divide the blades, and this I disclaim.

I am also aware that it has been heretofore proposed to journal two dashers to a dasher-rod, and to provide said dashers with radial blades inclined in opposite directions, to rotate the dashers in contrary directions, and this, also, I disclaim.

Having thus described my invention, I claim—

The combination of the threaded dasher-rod, the dashers journaled thereon at a suitable distance apart, said dashers being made of wood, and having radial inclined blades provided with correspondingly-inclined open slots dividing the blades, the blades and slots of one dasher being inclined in the opposite direction from the blades and slots of the other dasher, to cause the dashers to rotate in opposite directions, the metallic plates H, secured 75 to the opposing faces of the dashers, the sleeve I, on the rod between the dashers, and the nuts K, for securing the dashers in place, substantially as described.

In testimony that I claim the foregoing as my 80 own I have hereto affixed my signature in presence of two witnesses.

THOMAS H. ABERCROMBIE.
